UNITED STATES PATENT OFFICE

167,223

AIR CLEANER HEAD

William N. Patterson, Detroit, Mich.

Application July 25, 1951, Serial No. 16,015

Term of patent 14 years

(Cl. D9—2)

To all whom it may concern:

Be it known that I, William N. Patterson, a citizen of the United States of America and residing at the city of Detroit, county of Wayne, State of Michigan, have invented a new, original, and ornamental Design for an Air Cleaner Head, of which the following is a specification, reference being made to the accompanying drawings, forming part thereof.

Figure 1 is a top plan view of an air cleaner head embodying my new design.

Figure 2 is a bottom view of the head.

Figure 3 is a side view of the cleaner head.

Figure 4 is a front view thereof.

The dominant features of my design reside in the portions shown in full lines.

I claim:

The ornamental design for an air cleaner head, substantially as shown and described.

WILLIAM N. PATTERSON.
